UNITED STATES PATENT OFFICE.

ADOLPH E. HERMAN, OF TERRE HAUTE, INDIANA.

DESIGN FOR A WAGON-BODY.

SPECIFICATION forming part of Design No. 23,564, dated August 14, 1894.

Application filed June 26, 1894. Serial No. 515,788. Term of patent 7 years.

To all whom it may concern:

Be it known that I, ADOLPH E. HERMAN, a citizen of the United States, residing at Terre Haute, Indiana, have invented and produced 5 a new and original Design for Undertakers' Wagons, of which the following is a specification.

The accompanying drawing represents a perspective view of my design for an undertaker's wagon body.

The design consists of a body, the sides of which are rhomboidal, thus presenting front and rear edges inclining downwardly and forwardly, the sides being extended at the front 5 by a narrow portion with curved upper edges extending to the dash and a hood surmounting the front portion of the body and having curved front edges forming forwardly and upwardly curved continuations of the inclined edges of the rhomboidal sides and a top curving forwardly and downwardly and forming with the curved front of the hood a peak overhanging the foot rest compartment.

In the drawing A is the body portion, the 5 sides of which are in the general form of a rhomboid, that is the rear edge inclines down-

wardly and forwardly and the front edge is similarly inclined, until it merges into the curved upper edge of the sides of the foot rest extension. The rhomboidal effect is carried out however, by continuing the forward inclined edge by means of a bead. The sides are divided into rhomboidal panels. The sides have forwardly projecting reduced extensions, the upper edges of which are curved. 35 The forward part of the body is surmounted by a hood, the front edges of whose sides curve upwardly and forwardly over the reduced extension, meeting the forwardly and downwardly curved roof in an overhanging 40 peak. The sides and back of the hood are paneled.

I claim—

The design for a wagon body, as herein shown and described. 45

In testimony whereof I affix my signature in presence of two witnesses.

A. E. HERMAN.
